SYSTEM AND TRUCK FOR LOADING BOXED PRODUCE

Harold C. Pierce, Pomona, Calif.

Application February 17, 1941, Serial No. 379,266

18 Claims. (Cl. 214—65.5)

This invention deals in a general way with improved systems and apparatus for handling and conveying boxed produce, and particularly crown-packed fruits such as oranges, lemons and the like, contained in boxes having bowed lids and adapted, by reason of the configuration of the boxes, to be conveyed, loaded and transported in particular relative arrangement.

Taking citrus fruits as typical, the customary practice in handling and loading the boxed fruit for shipment, has been to truck or otherwise convey the crown-packed boxes from the lidding machine in the packing house, into box cars spotted nearby, and to arrange the boxes in the car on end and in transverse rows, usually two tiers deep, with the bowed lids of the boxes in each row facing the same side wall of the car, or with the boxes at either side of the row center, facing opposite side walls of the car. When thus arranged, the bowed lid of each box is adjacent or in engagement with the bottom of the next box toward one or the other side of the car, as the case may be.

Insofar as I am aware, the consistent practice heretofore has been to stack the boxes coming from the press lidded, on their sides and ordinarily about four high. Each box stack is then engaged by and loaded on a hand truck and thus conveyed into the car for placement as described above. In unloading the hand truck, the operator or car loader, is required to take the boxes from the truck, stand them on end, two high, and place them in proper relationship with respect to their bowed and bottom surfaces in transverse rows as aforesaid. Thus, this usual method involves considerable labor in first having to stack the boxes in horizontal positions as they are received from the lidding machine, and later to up-end and stack the boxes in different positions for arrangement in the car.

One of the primary objects of the invention is to simplify this customary method of handling and conveying the boxes from the lidding machine to the car, and to largely dispense with a number of box handling operations or manipulations, and consequently the time and labor normally required. In accordance with the invention, the boxes taken from the lidding machine are in the first instance arranged and stacked two high, with the bowed box lids facing in the same direction. Because of the easy portability of four boxes on a single hand truck, the boxes ordinarily will first be stacked in upper and lower pairs, with the crown of one engaging the bottom surface of the other box in each pair.

It will be recognized that by this method, the boxes are initially arranged and stacked in the same relative positions which they will occupy when finally loaded in the car. Conveyance of the boxes stacked in this manner, as distinguished from the usual arrangement, has necessitated development of an improved and different hand truck so designed and operated as to accommodate itself to the different box arrangement. It is with this improved truck that the present application is primarily and more particularly concerned.

The present truck may be described generally as comprising clamps, which individually may be of the usual type, adapted to engage and support the box load from the outside. The box supporting or clamping mechanism however differs from those heretofore used on the conventional stacks, in that it is adapted to support, and if desired to positively clamp the individual bottom boxes from their inside as well as outside surfaces. Accordingly, the clamping or supporting mechanism is made to enter the space between the adjacent bowed and bottom surfaces of the boxes, and preferably to be outwardly expandable into clamping engagement with the boxes. The invention contemplates also improvements with respect to hydraulic or fluid pressure actuated mechanisms for the clamps, and it may be mentioned that in this respect, the invention is not necessarily limited to trucks or clamping mechanisms specifically adapted to the particular form of box stack herein shown. Improvements in the truck mechanisms also include various additional features such as an automatic clamp locking device, means for laterally supporting the upper part of the load, and a device operable automatically to disengage and displace the truck from the load. All these various features can perhaps be explained to better advantage in connection with the later detailed description.

After the boxes taken from the lidded have been stacked on end and in pairs as described, the box load may be engaged by the truck and conveyed into the car. No further individual handling of the boxes is required for the reason that with the boxes prearranged on the truck, it is only necessary to direct the truck into such position that the boxes can be deposited in proper position in the transverse rows within the car, and to then disengage the truck.

Upon arrival of the car at its destination, it is made possible by the present truck to remove the boxes from the car in the same relative positions in which they were loaded into and car-

ried in the car. This again is in distinction to the usual method of unloading requiring the boxes to be stacked on their sides within the car in order that they may be handled by the unloading trucks. This operation is entirely obviated by the invention, resulting in further savings of time and labor, and also the damage and injury to the fruit and boxes that customarily results from rehandling and restacking the boxes in unloading the car.

Having explained the general method of loading and the advantages of the truck by reason of its adaptability to that method, I shall now proceed to a more detailed description of a typical and illustrative embodiment of the truck construction, as shown in the accompanying drawings. In the drawings:

Fig. 1 is a side elevation showing the truck as it is being applied to the box load;

Fig. 2 is a front elevation of Fig. 1, the upper boxes being broken away to show the adjustable retaining bar on the truck;

Fig. 3 is a fragmentary enlarged section on line 3—3 of Fig. 2;

Fig. 4 is a fragmentary elevation showing certain jaw operating parts of the truck, as viewed from line 4—4 of Fig. 1;

Fig. 5 is a fragmentary enlarged plan on line 5—5 of Fig. 2, showing the inner clamp arrangement;

Fig. 6 is an enlarged section on line 6—6 of Fig. 4, illustrating the upper end construction of the pedal and jaw releasing device;

Fig. 7 is a fragmentary front elevation as viewed from line 7—7 of Fig. 1;

Fig. 8 is a center cross-section on line 8—8 of Fig. 7;

Fig. 9 is a sectional view on broken line 9—9 of Fig. 7;

Fig. 10 is a horizontal section on line 10—10 of Fig. 7; and

Fig. 11 is a section taken on line 11—11 of Fig. 8.

As shown in Figs. 1 and 2, the preferred form of the invention is embodied in a truck particularly adapted and constructed to convey crown-packed boxes arranged side by side on end, with the load ordinarily two boxes high. As previously explained, use of the present truck obviates and renders unnecessary, much of the work required of the loader when handling the boxes according to the customary method of stacking and trucking them on their sides and ultimately loading them on end in the car. According to the system of loading herein contemplated, the boxes 15 coming from the lidding machine are arranged side by side on end, with the bulged crown 16 of one box adjacent to or engaging the bottom surface of the other box, so as to leave a space 17 therebetween. The boxes thus are prearranged in accordance with their relative positions in which they are to be finally loaded in the car, and most generally the boxes will be arranged as shown in Fig. 2, with the bulged crown or lid 16 of one box engaging the bottom surface 18 of the other box. It may be mentioned however that in some instances it may be desirable to truck the boxes with the bulged crowns of the boxes in each tier in engagement, particularly to meet conditions of center loading in the car.

The truck, generally indicated at 20, may have a usual frame structure comprising, for example, a pair of side rails 21 terminating in handles 22, and interconnected by cross bars 23, 24, 25 and

26, the latter projecting beyond the side rails at the bottom of the frame, as best illustrated in Fig. 7. Metal facings 27 are applied to the forward, load engaging surfaces of the side rails. The truck frame is mounted on wheels 28, the axles 29 of which are journaled within brackets 30 bolted at 31, 31a to a base 32, which in turn is bolted at 33, 31 and 31a to the side rails 21.

The load supporting parts comprise a pair of outer clamps 34 projecting forwardly of the frame beyond the side rails 21, and having at or near their front ends, inwardly projecting jaws or dies 35, see Fig. 2, adapted to be thrust inwardly beneath the bottom ends of the boxes, upon full inward movement of the clamps. It will be noted that the inner surfaces 34a of the clamps are beveled at an angle corresponding generally to the slope of the bulged box lids 16, thus permitting inward movement of the clamp adjacent the outer lid, a distance sufficient to permit engagement of the jaw 35 beneath the box. Clamps 34 are integral with plates 36 slideable transversely of the truck frame between member 26 and rollers 37 journaled on pins 38 within the side rails 21.

The outer clamps 34 are actuated by fluid pressure operated piston and cylinder assemblies generally indicated at 39, see Fig. 10, mounted on adjustable supports or carriers 40 movable along the frame member 25. Each of these carriers 40 comprises a pair of spaced plates 41 and 42 interconnected by bolts 43 and 44 about which are placed rollers 45 to facilitate transverse movement of the carriers 40 along frame member 25. For any given range of operation of the clamps 34, the carriers 40 are made variable by an adjusting mechanism, generally indicated at 47, comprising a nut or arbor 48 carried on a threaded shaft 49 journaled within bearing 50 attached to frame member 24, see Fig. 8, the lower end of the shaft being supported within a stationary socket 51. The arbor 48 is connected to each of the carriers 40 by toggle links 52 and 53 pivotally interconnected at 54 and pivotally attached at 55 to the arbor and at 56 to the carrier bolt 44, as shown in Fig. 9. Links 52 and 53 are held against pivotal movement in one direction by a stop flange 57 on link 53, thus normally providing a longitudinally rigid but breakable connection between the arbor and the carrier. When it is desired to move either carrier, together with the corresponding jaw 34, inwardly beyond a location to which such inward movement otherwise would be limited by the arbor, links 52 and 53 may be swung outward about pivot 54 to permit inward displacement of the carrier. Such manipulation of the parts may be made in the event the truck is being used to carry only one stack of boxes, and it is then desirable to displace the clamp 34 not in use, to give increased clearance at its side of the truck. Adjustment of the carriers 40 by the mechanism described, may conveniently be made by the operator, by turning handle 58 to rotate the screw shaft 49 and thereby raise or lower the arbor to vary the carrier spread.

Referring to Fig. 10, the hydraulically powered mechanisms 39 for operating the clamps 34, each comprises a cylinder 59 attached at 60 to the carrier plate 42 and containing a piston 61 through the outer portion of which is inserted a pin 62 received at 63 within an opening in the end portion 36a of plate 36. By introducing fluid under pressure through line 64 to the cylinder 59, piston 61 through its pin connection 62, moves the plate and clamp assembly inwardly relative to

both the frame and carrier 40. The inner end of the plate is guided in such movement by engagement with a roller 66 journaled on pin 67 between the carrier members 41 and 42. Maximum inward movement of the plate and clamp assembly relative to the carrier 40, is determined by engagement of the plate carried stop 68 with the side of the carrier, and outward movement of the plate and clamp assembly, is limited by engagement of pin 62 with the carrier, as shown in Fig. 10. Each outer clamp is moved inwardly against the resistance of a coil spring 70 connected at 71 to the piston carried pin 62, and at its opposite end to a bracket 72 integral with the cylinder 59. Upon release of the fluid pressure from the cylinder through conduit 64, spring 70 operates to return the jaw 34 to its outer position illustrated in Fig. 7.

The boxes 15 are supported at their inner faces exposed to space 11, by suitable means carried by the truck and adapted to be thrust into the space as the truck is applied to the load. While the invention broadly contemplates the provision of any suitable means of this character for supporting the inner faces of the boxes, I prefer to employ for this purpose a second set of movable jaws to insure maximum support and stability for the boxes, by positively engaging or gripping them at the inside as well as the outside. As best illustrated in Fig. 5, the inner clamp assembly comprises a pair of forwardly extending clamps 73 and 74 tapering toward their forward ends, which are formed with enlargements 75 in overlapping relation and shaped to provide, when in collapsed position shown, a substantially continuously curved end surface 76 to facilitate insertion of the clamps within space 11 between the boxes. Each clamp carries a laterally projecting jaw or die 77 which, when the clamps are spread apart as will presently appear, is thrust against the bottom portion of the adjacent box, in a manner similar to the action of the outer jaws 35, as previously explained.

Referring now to Figs. 7 and 8, jaws 73 and 74 are formed integrally with vertically extending arms 78 and 79 pivotally supported on bolts 80 to provide swinging mountings for the jaws. Bolts 80 serve also to attach to frame members 25 a plate 81 to the upper end of which the arbor screw socket 51 is welded. The hydraulic power cylinder and inner clamp actuating cylinder assemblies, are supported by a bracket structure 82 secured to plate 81 by bolts 83, and attached through the lower portion of plate 81 to the bottom frame member 26, by bolts 84.

The outer jaw actuating piston and cylinder assemblies 39, as well as the later described piston and cylinder assemblies for operating the inner clamps, are supplied with pressure fluid (e. g. a low viscosity oil) under control of the operator, from one or more power cylinders mounted on or cast integrally with the bracket structure 82. In order to provide for individual and selective operation of the clamps applicable to either of the bottom boxes, I preferably provide a pair of power cylinders 86 and 87 individually connected through conduits 64 with the outer clamp actuating cylinders 59. Cylinders 86 and 87 contain pistons 88 individually displaceable by the operation of foot pedals 89 pivotally mounted at 90 on arm extensions 91 of the bracket structure 82. Each pedal has forward and rear treads 92 and 93, and carries a depending lug or cam 94 which engages and depresses a piston 88 when the operator steps down on the tread 93. Each cam lug 75

84 has a squared end 84a which when the piston 88 is fully depressed, flatly engages the top of the piston and locks it in its depressed position, preventing displacement of fluid back into the cylinder until the pedal is released, and thereby causing the clamps to be locked in their box engaging or operative positions.

Referring now to Fig. 11, cylinders 86 and 87 communicate through passages 86 and 87 with the inner ends of cylinders 88 and 89 containing pistons 100 operatively connected to the inner pair of jaws 73 and 74. Pistons 100 carry transverse pins 101, the outer ends of which are received within openings 102 in the clamp arms with sufficient clearance to permit slight lost motion due to the swinging movement of the clamp. The opposite ends of pins 101 are interconnected by a coil spring 103 tending to resist movement apart of the pistons 100 and spreading movement of the clamps 73 and 74. Displacement of fluid from cylinders 86, 87 into cylinders 88, 89 moves pistons 100 outward, thus causing the clamp arms 78 and 79 to swing apart short angular distances about pivots 80. Maximum outward displacement of the arms is limited by their engagement with suitable stops 140 in the frame member 26. Spreading movement of the clamps 73 and 74 thrusts the jaws 77 beneath the box ends. Upon release of the foot pedals 89, permitting return displacement of fluid into cylinders 86 and 87, spring 103 moves pistons 100 inwardly and withdraws the jaws 77 from operative engagement with the load.

The invention further provides in conjunction with the hydraulic clamp operating system, a device for automatically releasing the power pistons 88 from their locked or depressed positions when the truck is to be disengaged from the load. Referring to Figs. 4 and 8, I provide a pedal releasing device, generally indicated at 104, comprising a rod 105 extending through a guide 106 cast integrally with cylinders 88 and 89, and carrying a base plate 107a normally bearing against the floor. Rod 105 carries on its upper end a tubular head 107 movable downwardly on the rod against the resistance of coil spring 108 a distance permitted within the limits of engagement of rod carried pin 109 within slot 110. Bodily downward movement of the rod 105 relative to the guide casting 106 is limited by engagement of the rod flange 111 with the upper end 106a of the casting. The operation of the pedal releasing device 104 can perhaps later be explained to better advantage in describing the operation of the truck as a whole.

In applying the truck to the load, the outer bowed box crown 16 may be at one side or the other of the load, depending upon the side from which the load is approached, or the particular position in which it is to be arranged on the truck for placement in the car. In order to laterally support the upper tier of boxes against movement on the truck I provide a retaining bar 112, see Fig. 2, having angular end portions 113 adapted to be brought into engagement with the outer sides of the load. Bar 112 has pin and slot connections 114 with the side rails 12 so that the bar may be shifted laterally of the truck in either direction, depending on which side the bulged box crown 16 is placed. End portions 113 of the bar advantageously may consist of angular pieces pivotally connected at 115 to the body of the bar so as to be capable of swinging relative thereto. When the truck is being wheeled in inclined position toward the load, the inclination of

the truck is sufficient to cause the pieces 113 to assume the dotted line positions 113a, the centers of gravity of the pieces lying at the outside of the pivot points 115. As the truck is applied to the load, the inner ends 113b are pressed against the boxes, causing the outer portions 113 to be swung inwardly to the solid line position shown, thus simultaneously engaging the load and centering the bar relative to the load.

The invention contemplates a further improvement in the form of a device whereby after the truck clamps are disengaged from the load, the truck becomes automatically displaced by movement away from the load to a position as illustrated in Fig. 1. In a simple and preferred form, the truck displacing device comprises a pair of angular arms 116 pivotally mounted at 117 on the side rails 21 and interconnected at their lower ends by a cross-member 118. Normally the arm and cross-member assembly is thrust forward to the position shown, as determined by engagement of the arm with stop pins 119, by coil springs 120 connecting the upper ends of the arms with the frame. As the truck is applied to the load and the boxes are tilted back into flush engagement with the truck frame according to the customary manner, arms 116 are displaced inwardly into substantial parallelism with the side rails 21, with plate 118 confined between the surface of the truck face plates 27 and the adjacent surfaces of the lower boxes. It is important to observe that the thrust of coil springs 120 exerted through arms 116 and member 118 against the load, is applied thereto at an elevation sufficiently low that the counteractive effect of such thrust on the truck is to cause the truck to move away from the load with the truck remaining in its normal vertical position as shown in Fig. 1. In this manner the truck is prevented from tilting while being retracted from the load, thus assuring withdrawal of the clamps, and particularly the inner clamps 73 and 74, without binding engagement with the load which would otherwise occur should the truck become tilted.

In describing its operation, assume that the truck first is moved against the box load in the aspect of Fig. 1, with the clamps and their operating parts in their normal positions of Figs. 4 to 11. When the bottom of the truck is moved flush against the load, (forcing arms 116 and plate 118 into retracted position as previously described) the operator steps on the foot pedals 89 to actuate the clamps by the displacement of fluid from cylinders 86 and 87 into each pair of the clamp operating cylinders 59, 98 and 59, 99. Since the pistons in each of said pairs of cylinders are actuated by fluid displaced from the same power cylinder 86 and 87, the clamps being applied to either box are actuated uniformly and by the same fluid pressure, thus assuring proper centering of the box with relation to the clamps and secure engagement and retention of the boxes by the clamps. For many reasons it may be desirable to release the clamps from the load before such time as the load and truck may be tilted back to carrying position. This purpose is served by the pedal releasing device 104 through the reaction of the spring supported head 107. Downward movement of the pedals 89 is resisted by coil spring 108 through engagement of the head 107 by the inwardly projecting pedal flanges 122. Consequently, while the truck is in the positions of Figs. 1 and 8, spring 108 will operate to return the pedals to

their raised positions regardless of how far down they may have become pressed.

With the clamps firmly applied to the load and while the pedals 89 are depressed, the operator 5 grasps the top of the load and tilts the truck backward on its wheels. As a result, rod 105 of the pedal releasing device remains supported on the floor and the pedals are swung away from the head 107 to relieve its upward thrust against the pedals. The latter thereafter remain locked 10 in their piston depressing positions by engagement with the squared shoulders 94a with the tops of the pistons, while the truck is being wheeled in its inclined position.

Upon reaching the load destination, the truck 15 may be released from the boxes simply by tilting the load forward to resting position on the floor and returning the truck to the upright position of Fig. 1. As the truck approaches this 20 upright position, the spring supported head 107 on the pedal releasing rod 105 comes into engagement with flanges 122 to swing the pedals upwardly to their clamped releasing positions. Springs 10 and 103 immediately retract the clamps from the 25 boxes and cause fluid to be displaced from the clamp actuating cylinders back through conduit 64 into the power cylinders 86 and 87. Immediately upon release of the clamps, the truck is automatically retracted from the load to substantially 30 the position of Fig. 1, by the thrust of arms 116 and plate 118 against the load in the manner previously explained.

For the purpose of describing and illustrating the invention, I have shown a typical embodiment having various features and details that 35 may be desirable in a truck capable of serving all the different purposes for which these features and details are intended. It is to be understood, however, that this showing is typical only, and 40 that various individual features may be dispensed with, and various changes and modifications otherwise made without departure from the invention in its intended spirit and scope.

I claim:

45 1. A truck for conveying bulged crown boxes arranged side by side on end with the crown of one box adjacent the other box to form a space between the boxes, said truck comprising a frame, box holding means comprising bodily movable clamps engageable with the outer faces of said boxes at the sides of the truck, members adapted to be inserted within said space and bodily movable apart into supporting engagement with the box faces exposed thereto, and means for manually operating said clamps and members.

50 2. A truck for conveying bulged crown boxes arranged side by side on end with the crown of one box adjacent the other box to form a space between the boxes, said truck comprising a frame, and box holding means comprising bodily movable members projecting forwardly of the frame and engageable with the outer faces of said boxes at the sides of the truck and with inner faces of the boxes exposed to said space, and means for transmitting fluid pressure to actuate said members in their bodily movement.

55 3. A truck for conveying bulged crown boxes arranged side by side on end with the crown of one box adjacent the other box to form a space between the boxes, said truck comprising a frame, box holding means comprising movable members engageable with the outer faces of said boxes at the sides of the truck, supporting means adapted to be inserted within said space and engageable with the box faces exposed thereto, and

manually controlled hydraulically actuated means for operating said members and comprising a foot pedal and piston assembly operable to transmit fluid pressure to actuate said members.

4. A truck for conveying bulged crown boxes arranged side by side on end with the crown of one box adjacent the other box to form a space between the boxes, said truck comprising a frame, box holding means comprising movable clamps engageable with the outer faces of said boxes at the sides of the truck, members adapted to be inserted within said space and movable into supporting engagement with the box faces exposed thereto, and manually controlled hydraulically actuated means comprising a foot pedal and piston assembly operable to transmit fluid pressure to produce bodily movement of said clamps and members.

5. A truck for conveying bulged crown boxes arranged side by side on end with the crown of one box adjacent the other box to form a space between the boxes, said truck comprising a frame, a plurality of clamp members projecting forwardly from the frame and engageable with the outer faces of said boxes at the sides of the truck and with inner faces of the boxes exposed to said space, foot pedal means, and means actuated thereby to bring said clamp members into supporting engagement with the boxes.

6. A truck for conveying bulged crown boxes arranged side by side on end with the crown of one box adjacent the other box to form a space between the boxes, said truck comprising a frame, a pair of outer clamps projecting forwardly from the frame and engageable with the outer faces of said boxes at the sides of the truck, a pair of inner clamps projecting from the frame and adapted to be inserted within said space between the boxes, and foot operated means mounted on the frame for actuating said inner and outer clamps.

7. A truck for conveying bulged crown boxes arranged side by side on end with the crown of one box adjacent the other box to form a space between the boxes, said truck comprising a frame, a pair of outer clamps projecting forwardly from the frame and engageable with the outer faces of said boxes at the sides of the truck, a pair of inner clamps projecting from the frame and adapted to be inserted within said space between the boxes, hydraulically operated means for actuating the inner and outer clamps engageable with one of said boxes, hydraulically operated means for actuating the inner and outer clamps engageable with the other box, and foot actuated means for controlling both of said hydraulically operated means.

8. A truck for conveying bulged crown boxes arranged side by side on end with the crown of one box adjacent the other box to form a space between the boxes, said truck comprising a frame, box holding means comprising members engageable with the outer faces of said boxes at the sides of the truck and with inner faces of the boxes exposed to said space, manually controlled means for operating said box holding means, locking means for retaining said holding means in operative position, and means for releasing said holding means by bodily tilting movement of the truck.

9. In a box conveying truck of the character described, the combination comprising a wheeled frame adapted to be moved against a box load, clamping means operable to engage and disengage the load, and self-acting means carried by

the truck and operable upon disengagement of the clamping means to move the truck away from the load, the last mentioned means comprising a member mounted on the truck and movable toward the frame by application of the truck to the box load, and yielding means resisting such movement of the member.

10. In a box conveying truck of the character described, the combination comprising a wheeled frame adapted to be moved against a box load, clamping means operable to engage and disengage the load, and spring actuated means carried by the truck and operable automatically upon disengagement of the clamping means to bear against the load and move the truck away from the load.

11. In a box conveying truck of the character described, the combination comprising a frame, a movable member adapted to engage and support a box against movement relative to the frame, manually controlled means for transmitting fluid pressure to actuate said member, means for locking said member in its box supporting position, and means for releasing said fluid pressure to release said locking means by bodily tilting movement of the truck.

12. In a box conveying truck of the character described, the combination comprising a frame, a movable member adapted to engage and support a box against movement relative to the frame, a piston for transmitting fluid pressure to actuate said member into its box supporting position, means for locking said piston in its corresponding position, and means for releasing said fluid pressure to retract said member from its box supporting position by bodily tilting movement of the truck.

13. A truck for conveying bulged crown boxes arranged side by side on end with the crown of one box adjacent the other box to form a space between the boxes, said truck comprising a frame, box holding means carried by the frame and comprising members projecting forwardly of the frame and engageable with the outer faces of said boxes at the sides of the truck and with inner faces of the boxes exposed to said space, and means for producing relative bodily movement of said members to press against said inner and outer faces of the boxes.

14. A truck for conveying bulged crown boxes arranged side by side on end with the crown of one box adjacent the other box to form a space between the boxes, said truck comprising a frame, box holding means carried by the frame and comprising movable members projecting forwardly of the frame and engageable with the outer faces of said boxes at the sides of the truck, supporting means adapted to be inserted within said space and engageable with the box faces exposed thereto, and means for moving said members bodily toward the boxes to tightly confine the boxes between said members and said supporting means.

15. In a box conveying truck of the character described, the combination comprising a frame, a pair of wheels having their common axis offset rearwardly of the frame, a member projecting forwardly of the frame and adapted to move into engagement with and to support a box against movement relative to the frame, a fluid pressure displaceable element for actuating said movable member, and manually controlled means positioned between the frame and said wheel axis and operable to develop fluid pressure for communication to said element.

16. In a box conveying truck of the character described, the combination comprising a frame, a pair of wheels having their common axis offset rearwardly of the frame, a member projecting forwardly of the frame and adapted to move into engagement with and to support a box against movement relative to the frame, a fluid pressure displaceable element for actuating said movable member, yielding means resisting displacement of said element in a direction causing movement of said member into engagement with the box, and manually controlled means positioned between the frame and said wheel axis and operable to develop fluid pressure for communication to said element.

17. In a box conveying truck of the character described, the combination comprising a frame, a pair of wheels having their common axis offset rearwardly of the frame, a pair of members projecting forwardly of the frame and movable oppositely to engage and support the truck box load against movement relative to the frame, in-

5 dividual fluid pressure displaceable elements operatively connected to said members, and manually controlled means positioned between the frame and said wheel axis and operable to develop fluid pressure for communication to said elements.

10 18. In a box conveying truck of the character described, the combination comprising a frame, a pair of wheels having their common axis offset rearwardly of the frame, a pair of clamps projecting forwardly from the bottom portion of the frame and movable transversely to support the truck box load against movement relative to the frame, individual piston and cylinder assemblies 15 operatively connected to said clamps, means communicating with said assemblies for developing fluid pressure to actuate the clamps, the last mentioned means being positioned between the frame and said wheel axis, and foot pedal means 20 overlying the wheel axis and adapted to actuate said fluid pressure developing means.

HAROLD C. PIERCE.
